UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

INK FOUNTAIN FOR PRINTING MACHINES.

Application filed August 4, 1923. Serial No. 655,770.

This invention relates to a fountain for ink and the principal objects thereof are to provide a new and improved construction of the same in which the machining of the contacting parts will be avoided and they can be assembled by an unskilled mechanic and yet will fit accurately and operate effectively without shortening the life of the machine.

More specifically, the invention involves new and improved means for mounting the fountain roll in permanent bearings and a back and scraper blade also, and means whereby the fountain itself can be mounted on the frame in accordance with the same principles without machining the parts.

Additional objects and advantages of the invention will appear hereinafter.

Reference is to be had to the accompanying drawings, in which

Fig. 1 is a plan of an ink fountain with certain parts removed to show the construction, the same being made in accordance with this invention;

Fig. 2 is a front elevation of the same;

Fig. 3 is an end elevation;

Fig. 4 is an end elevation of one of the fountain roll brackets removed from the rest of the machine and ready to be placed in position with the roll supported thereby;

Fig. 5 is a fragmentary plan of one end of the fountain back;

Fig. 6 is a plan of the bracket carrying the bearing for the end of the fountain roll shaft; and

Fig. 7 is a sectional view of the back.

It is to be understood that this fountain is to be mounted on a printing machine frame 10 to be used for the usual purposes in the usual way. Only a fragment of the cast iron frame of the press is shown as the invention is independent of the rest of the printing machine. This frame is provided with a preferably horizontal surface 11 on which the fountain is to be supported, the support for one end of the fountain only being shown in the drawings. It is to be understood that the other end is supported in some way. Heretofore it has been necessary to machine this to provide a true surface for the fountain to rest on and the under side of the fountain was machined at the same point for the same purpose. According to this invention, this machining is avoided. When this machine frame 10 is cast, instead of being provided with excessive metal on the surface

11 designed to be planed off to provide a true seat for the fountain, it is provided with an undercut recess 12 at that point and contains less metal in the original casting than is required for the support of the fountain in the proper plane. This saves some cast iron.

After the machine frame is cast a metal mold or die, not shown, is placed over or adjacent to the surface 11. It is so shaped that a body of soft metal 13 can be cast in the mold and in the undercut recess 12 so that it will be held in the undercut recess permanently and will project above it. This mold has a flat, or at least a regular surface against which the metal is cast and which provides a flat top for this metal accurately finished in the casting operation to constitute a supporting seat. This is accomplished by employing for the metal 13 a non-shrinking and non-expanding metal or alloy, such for example as antimonial lead, an alloy of lead and antimony that neither contracts nor expands materially on solidifying from a molten state. It can be cast at a low temperature of 500° to 600° F. It solidifies quickly and has sufficient strength and hardness to sustain the weight and pressure to which it is subjected in this machine. This flat body of metal 13 thus constitutes a supporting seat for one end of the ink fountain. A seat exactly like it is furnished on the other side of the frame for the other end. This is accomplished without any machining operations, the finishing of the surfaces being done entirely by casting.

The fountain box 15 is provided with two arms 16 exactly opposite each other and projecting outwardly therefrom. In the casting of this fountain box 15 from iron an undercut recess 18 similar to the recess 12 is formed. After the casting is produced a metal mold is placed over this undercut recess and so shaped that the same alloy can be cast in this recess and form a projecting seat 17 having a flat surface fitting the surface of the seat 13. These are cast to the same size and having preferably flat surfaces fitting each other. But if desired these surfaces can be made of some other shape so long as they fit accurately. In the assembling of the parts the fountain box 15 is placed in position with its two seats 17 resting on the seats 13. Then these parts can be bolted together by inserting bolts through holes 19 left in the process of casting to pre-

vent all relative motion. This furnishes an accurate way of providing for mounting the fountain box on the frame in a predetermined position and securing accuracy in the placing thereof without machining the frame or the fountain box. Of course the molds or dies used have to be machined accurately but they are used over and over.

The fountain box 15, as cast is provided in its end wall 23 with two concave recesses opposite each other, each one having considerable width and each provided with an undercut recess 20. I have shown these recesses or seats as of arcuate form, almost a semi-circle. They are arranged symmetrically with respect to each other, one directly opposite the other. After the iron casting constituting the main body of the ink fountain box 15 is cast and cooled, a metal mold is placed over each of these recesses in such a way as to provide a space adjacent thereto. The inner surface of this mold is of finished metal. An alloy such as above described is then cast in each of these molds. It forms two concave supporting seats 22 of the alloy finished on their concave surfaces in the casting process and not requiring any further finishing. The edges also are finished flat by the walls of the mold in which they are cast. I now cast a pair of fountain roll brackets 25 having a general shape similar to the interior of the two seats 22 but of smaller radius and formed of cast iron. These are provided with undercut recesses 26 and coated with the alloy described above to form a seating surface 27 all around the convex lower portion of the bracket. At the same time or subsequently a flat seat 28 of the same alloy is provided on the top edge of each bracket near one end. The exterior curved surface of the soft metal 27 is formed to fit exactly the concave surface of one of the seats 22 so that these brackets can be put into the seats 22 and the parts can be united by bolts 29 and held firmly in position in that manner. In this way these brackets 25 are fitted in position on the ends of the ink fountain without resorting to machining methods at all and yet they are accurately fitted and seated in position and firmly held. I also provide a flat coating 34 on one side formed of the same soft metal and having a flat outer bearing surface for engaging the flat end of the fountain roll 33. I also provide each of the brackets 25 with an opening 30 therethrough and I line this opening with a lining of soft metal 31 in the same manner as above described by casting it into the opening and securing an inner surface of exactly cylindrical shape by means of a hard metal core employed in the casting operation. These furnish bearings for the shaft 32 of the fountain roll 33 and permit of the mounting of the fountain roll in these brackets and bearings so that it is

permanently and accurately held in position although it is to be understood that the bolts 29 can be loosened and the fountain roll with its shaft and the two brackets 25 removed. The bodies of soft metal 27 and 34 are shown as cast integral with each other at one casting operation.

On each of the arms 16, above mentioned, beyond the seat 17 I provide a projection 35 and form upon it a flat supporting seat 36 of the same alloy and in the same manner as described in connection with the formation of the seat 13. I also provide a bearing 37 having an accurately cast soft metal lining 38 for the shaft 32 with a projection 39 having a soft metal seat 40 formed on it in the same way as the seat 17 above described and fitting the supporting seat 36. This is mounted in position on this seat so as to give a proper support to the bearing bracket 37. One of these is mounted on each end of the machine in this manner near the ends of the shaft which is also supported by the bearings 31 near the ends of the fountain roll.

The parts so far described constitute means for accurately supporting the fountain itself on the frame of the printing machine and for accurately mounting and supporting the fountain roll in the fountain so as to be capable of rotating on its own axis in the usual way. All these results are accomplished without machining either the frame of the printing machine or the fountain itself. It will be understood that the fountain roll and its shaft may be machined accurately in the usual way or otherwise constructed so as to have smooth surfaces, those of the shaft fitting in the bearings 31 and 38. In this way the parts can be assembled without resorting to machining methods or without requiring highly skilled labor for connecting them.

In the assembling of the parts so described the fountain roll with its shaft 32 is provided with two fountain roll brackets 25 by placing them on over the ends of the shaft so that the shaft passes through the perforations 30 and has its bearings in the soft metal linings 31. These fountain roll brackets are moved along the shaft up against the fountain roll so that the seating body of soft metal 34 on each contacts with the flat end of the roll if desired, or it can be spaced therefrom. Then these brackets 25 are set down into the seats 22. Thus the seating bodies of metal 27 register with the seats 22 and the bolts 29 are inserted and fastened up. This firmly and accurately mounts the roll in position on the box.

The two brackets 37 are mounted on the ends of the shaft 32 so that the latter has its bearings in the linings 38. Then these brackets 37 are brought inwardly or outwardly as necessary and turned to the proper angle so that the seats 40 rest on the seats

36 and any proper fastening bolts or the like are inserted as in the usual cases to hold them in position. Thus there are four bearings for the shaft 32 at wide distances apart 5 to hold it and prevent vibration.

The assembled fountain box 15 is now located in position on the printing press frame 10 with the seats 17 in contact with the seats 13 and in registration therewith, 10 and bolts or other fastening devices placed in the perforations 19. This firmly secures the fountain box to the frame.

It will be seen that these parts are assembled easily and rapidly, and without the 15 use of skilled labor, and that no finishing of any of the parts is required except the fountain roll shaft, and in some cases the fountain roll itself.

I also carry out similar principles in the 20 mounting of the scraper blade and the back on which it is carried. For this purpose the fountain box 15 is provided with two integral bosses 42 at opposite ends and near one side. In the casting of the fountain 25 box 15 these bosses are provided with a central cylindrical passage 41 and an undercut recess 45 on the inside surface. This undercut recess is filled and a projecting bearing seat 46 formed and the passage 41 lined with the same soft metal at 44 in accordance with the process above described. This can be done in one operation having the lining or bearing 44 and seat 46 integral.

Now, the fountain back 47 is formed of 30 cast iron and provided with a pair of opposite arms 48 each having a deep recess 49 as cast. This recess is lined with this soft metal to form a cylindrical bearing 50 and provided with a projecting flat circular bearing seat 51 of the soft metal preferably integral therewith. These two seats at the 35 opposite ends of the back are formed in alignment by properly locating the molds in which they are cast. Obviously each has a smooth inner bearing 50 of cylindrical shape and a flat circular seating surface on the outside. The diameter of this bearing surface 50 is the same as the diameter of the linings of the two perforations 44. The 40 circular flat bearing surfaces 46 and 51 are of equal extent and fit each other accurately.

Also on the fountain back is located an 45 integral arm 52 at each end. These arms are provided with two seats 53 of soft metal of the same size and shape as the two seats 28 on the fountain roll brackets 25 above mentioned, the process of introducing it being the same as that above described. Now the fountain back is mounted in position by 50 placing it so that the two seats 53 rest accurately on the two seats 28. Also, the two parts 51 and 46 on the two ends are brought into registration with each other. Two pins 54 are fitted in the linings of the 55 perforations 44 and the recesses 49 respec-

tively. These pins constitute pivots on which the fountain back can swing and the seats 28 constitute supporting seats for the back to hold it in place.

On the back 47 at a distance from its 70 front is placed a flat seat 55 of soft alloy or metal as above described and against it by means of a bar 56 and screws 57 is secured a scraping blade 58. This also therefore is held in position without the necessity 75 of machining the parts of the back 47. In the back 47 at two or more places along its forward edge are cast inclined perforations 60 and at the bottom of the same are cast bodies of soft metal 61 about a master screw, 80 not shown, so that these bodies of metal are provided with an internal screw thread when the master screw is removed. Then adjusting screws 62 are threaded into these threaded bearings 61. These screws 62 rest on 85 top of the scraper blade 58 and adjust it toward the surface of the fountain roll.

In this way a large amount of the ordinary machining expense, substantially all of it, is eliminated and yet all the advantages 90 of having accurately planed and turned surfaces are secured and there is even less danger of any inaccuracy or of a part of a machine being thrown away on account of some error in the machining. 95

Although I have illustrated and described only certain forms of the invention and shown the various features as made in only one way, I am aware of the fact that modifications can be made therein by any person 100 skilled in the art without departing from the scope of the invention as expressed in the claims. Therefore, I do not wish to be limited to the exact form of the details herein shown and described but what I do 105 claim is:—

1. The combination with a printing press frame and an ink fountain box adapted to be supported thereby, of independently cast bodies of relatively soft metal permanently 110 united with the respective parts of the frame and box, one being seated on the other, the total thickness of the softer metal of the two parts occupying the space between the adjacent surfaces of the printing press frame and the ink fountain box. 115

2. The combination with a printing press frame having seats of relatively soft metal cast thereto, of an ink fountain box having seating surfaces of soft metal cast thereon and positioned so as to register with the seats on the printing press frame, whereby the seating surfaces are adapted to rest on the seats to support the fountain box from the frame. 120

3. The combination with a printing press frame having seats of relatively soft metal cast thereto and projecting therefrom, of an ink fountain box having arms on opposite sides, each having a seating surface of soft 125

metal cast on the under side thereof and at the same distance apart as the seats on the printing press frame, said seats and seating surfaces being formed to fit each other, whereby the seating surfaces are adapted to rest on the seats to support the fountain box from the frame.

4. The combination with a printing press frame having a supporting portion provided with a seat of relatively soft metal cast thereon in permanent position and provided with a top seating surface shaped in the mold in which it is cast without machining, of an ink fountain box having a downwardly projecting seat of soft metal cast on the bottom thereof and projecting therefrom and having a seating surface at the bottom finished in the casting mold and of such form as to fit the seating surface on the seat of the frame for locating and supporting the fountain box on the frame.

5. In an ink fountain, the combination with a fountain box for containing the ink, said box having a pair of opposite recesses near its ends lined with a comparatively soft metal cast permanently thereto and provided in the act of casting with seating surfaces requiring no finishing, of a pair of fountain roll brackets of a shape corresponding with the shape of said seats and each having a seating layer on its lower surface of soft metal permanently united thereto in the act of casting and provided with an external cast surface of the same dimensions as the internal surface of one of said seats and exactly fitting the same, and means on said fountain roll brackets for supporting the opposite ends of the fountain roll, whereby said brackets can be placed on said seats and secured thereto and will constitute firm and accurate supports for the fountain roll without necessitating the machining of the contiguous surfaces of the box and brackets.

6. In an ink fountain, the combination with a fountain box having a pair of soft metal seats located adjacent to the end thereof and permanently united with the box and having die cast seating surfaces, of a pair of fountain roll brackets adapted to be seated thereon and each having a permanent cast layer of soft metal on their under surfaces and having a cast finished surface fitting the seating surface of the first named soft metal linings, whereby said fountain roll brackets can be seated thereon and accurately held in position thereagainst, means for holding the fountain roll brackets in position, each of said fountain roll brackets having a perforation therethrough provided with a lining of soft metal having a true cast cylindrical inside surface, said surfaces being located in alignment opposite each other, and a fountain roll having a shaft adapted to be received in said cylindrical soft metal linings and to fit the same with substantial accuracy.

7. In an ink fountain for a printing press, the combination with a fountain box, of a pair of fountain roll brackets detachably mounted thereon, each of said brackets having a perforation therethrough, of a complete soft metal lining cast in one piece in each of said perforations with a true cylindrical inside bearing surface, and a fountain roll having a shaft fitting in said linings, whereby the fountain roll and the two brackets can be assembled outside the machine and then placed in the machine together and the brackets fixed thereto. 70

8. A fountain roll bracket of cast metal having a perforation therethrough, a convex bottom surface and a flat surface on one side and having cast thereon a continuous layer of soft metal covering the entire convex lower surface and the flat surface all in one casting, the soft metal being cast with a finished flat surface on the exterior of the side thereof and a finished convex surface on the bottom thereof, said bracket having cast soft metal bearings, whereby the shaft of the fountain roll fitting said bearings can be placed therein and bear thereon, and the finished flat end of the fountain roll can bear against the flat surfaces on the sides of said brackets, and whereby the brackets and roll can be mounted in the fountain in a permanent position. 80

9. In an ink fountain for a printing machine, the combination with the fountain box and means for detachably mounting a fountain roll therein without machining the parts of the box comprising a pair of fountain roll brackets located at opposite ends of the box, each having an exterior surface along the bottom thereof of soft alloy cast thereon in finished form to permit of providing for locating and fixing the brackets in position on the box, of a soft metal seat cast in finished form on the top of each of said brackets, a fountain back having on the bottom thereof a pair of soft metal seats cast in finished form thereon and having lower surfaces fitting and adapted to rest upon said seats on the brackets, thus supporting the fountain back, and means for pivoting the back to the box at a distance 105 from its supports on the brackets. 100

10. In an ink fountain for a printing machine, the combination with the fountain box and means for detachably mounting a fountain roll therein without machining the parts of the box, of a fountain back having on the bottom thereof a pair of soft metal seats cast in finished form thereon and adapted to rest upon said means, and means for pivoting the back to the means at a distance 120 from its supports on said means. 110

11. In an ink fountain, the combination with the fountain box of cast iron having a pair of opposite bosses extending upwardly from its ends, in parallel planes, each being 125

- provided with a perforation, said perforations being in longitudinal alignment, and a lining of soft non-shrinking metal cast in finished form permanently through each boss to provide a finished cylindrical bearing therethrough, of a fountain back having a pair of arms projecting oppositely from its rear end, each being provided with a depression, a soft non-shrinking metal lining cast in finished form in each of said depressions projecting from the face of the arm and having a cylindrical socket therein adapted to register with the perforation in one of the bosses and having a flat soft metal seat integral therewith on the end of the arm adapted to fit against the seat on one of the bosses, and a pair of pivot pins each extending into one of said perforations and through one of said seats into the adjacent socket in the fountain back, whereby said fountain back is pivoted to the box without the necessity of finishing any of the surfaces except the pivot pins. 6 70
- 10 12. In an ink fountain, the combination with the fountain box of cast iron having a pair of opposite bosses extending upwardly from its ends, each being provided with a perforation, said perforations being in longitudinal alignment, a lining of soft metal cast in finished form permanently through each boss to provide a finished cylindrical bearing therethrough, and a flat seat on the inner side of each box, of a fountain back having a pair of arms projecting oppositely from its rear end, each being provided with a depression, a soft metal lining cast in finished form in each of said depressions projecting from the face of the arm and having a cylindrical socket therein adapted to register with the perforation in one of the bosses and of the same diameter and having a flat seat integral therewith on the end of the arm adapted to fit against the seat on one of the bosses, and a pair of pivot pins each extending into one of said perforations and through one of said seats into the adjacent socket in the fountain back, whereby said fountain back is pivoted to the box by said pins without the necessity of finishing any of the surfaces except the pivot pins. 15 80
- 15 13. In an ink fountain, the combination with the fountain box of cast iron having a pair of opposite bosses, each being provided with a perforation, said perforations being in longitudinal alignment, and a lining of soft metal cast in finished form permanently through said bosses to provide a finished cylindrical bearing therethrough, of a fountain back having a pair of arms each being provided with a depression, a soft metal lining cast in finished form in each of said depressions having a cylindrical socket therein adapted to register with the perforation in one of the bosses, a pair of pivot pins each extending into one of said perforations and into the adjacent socket in the fountain back, whereby said fountain back is pivoted to the box by said pins without the necessity of finishing any of the surfaces except the pivot pins. 20 85
- 20 14. In an ink fountain, the combination with the fountain box of cast iron having a pair of opposite perforated bosses, of a fountain back having a pair of arms each being provided with a depression having a cast socket, a pair of pivot pins each extending into one of said perforations and into the adjacent socket in the fountain back, and means whereby said fountain back is pivoted to the box by said pins without the necessity of finishing any of the surfaces except the pivot pins. 25 90
- 25 15. In an ink fountain for a printing press, the combination with the fountain box, of a fountain back having a seat of soft metal permanently united thereto and having a surface finished in the act of casting, a scraper blade seated against said surface, means for fixing the scraper blade to the back against said soft metal surface, and means for regulating the position of the edge of the blade. 30 95
- 30 16. In an ink fountain, the combination with the fountain box, of a fountain back pivoted thereto and having no machine finished surfaces, said back having a seat of soft metal permanently united thereto and having its lower surface finished in the act of casting, a scraper blade seated on said surface, said back being provided with a plurality of perforations therethrough located in a position substantially over the free edge of the blade, a body of soft metal cast in each of said openings with a screw thread therein produced in the act of casting, and a corresponding number of adjusting screws threaded in said screw threaded openings for engaging the blade and adjusting it. 35 100
- 35 17. In an ink fountain for a printing press, the combination with a fountain box, of a cast iron back pivoted thereon and having a surface that is cast in a smooth finished condition, a scraper blade, and means for mounting the blade on said cast surface of the back against which the blade is fixed. 40 110
- 40 18. In an ink fountain for a printing press, the combination with a fountain box, of a cast iron back pivoted thereon, said back having a seat that is cast in a finished condition, scraper blade and means for mounting the blade on said cast seat of the back against which the blade is fixed. 45 115
- 45 19. In an ink fountain, the combination with a fountain box having means for fixedly uniting it to a printing machine frame and locating it in accurate position thereon without any machined surfaces and having an arm projecting therefrom at each end, of a soft metal seat permanently cast on the top of each of said arms and having seating sur- 50 120

- 6 being supported by said seating surfaces, each bracket having a perforation therethrough provided with a lining of soft non-shrinking metal united thereto by casting and finished on the interior in the act of casting to provide a cylindrical bearing in one piece, a fountain roll having a shaft projecting from its opposite ends and fitting in said bearings and adapted to be supported thereby, and means for fastening the bearings on the arms.
21. In an ink fountain for a printing press, the combination with a fountain box and an ink roll therein having a shaft, of two pairs of complete cylindrical soft metal bearings each cast in finished form in one piece and spaced apart directly supporting and contacting with the shaft at its ends and near said roll.
22. In an ink fountain for a printing machine, the combination with the fountain box and means for detachably mounting a fountain roll therein without machining the parts of the box, of a fountain back having a pair of soft metal seats cast in finished form thereon and adapted to be attached to said box.
23. In an ink fountain for a printing machine the combination of an ink holding receptacle, a roll for feeding the ink therefrom, and a blade for regulating the flow of ink, each of said elements having soft metal seats so applied and positioned that the whole may be assembled without machining the parts thereof.
- In testimony whereof I have hereunto affixed my signature.
- HENRY A. WISE WOOD.
